CLAIM

The ornamental design for a game controller having a game controller touchpad, as shown and described.

DESCRIPTION

FIG. 1 is a top, front, right perspective view of a game controller having a game controller touchpad.

FIG. 2 is a bottom, front, right perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof;

FIG. 8 is a left side elevation view thereof;

FIG. 9 is an exploded front elevation view of the game controller having a game controller touchpad; and,

FIG. 10 is a rear elevation view of the game controller touchpad with the game controller removed for ease of illustration.

The broken lines shown in the drawings depict portions of the game controller having a game controller touchpad that form no part of the claimed design.
